DESIGN FOR A CHILD'S SLIPPER

Max Linder, Brooklyn, N. Y.

Application April 18, 1939, Serial No. 84,368

Term of patent 3½ years

To all whom it may concern:

Be it known that I, Max Linder, a citizen of the United States of America, residing in New York city, in the Borough of Brooklyn, county of Kings, and State of New York, have invented a new, original, and ornamental Design for a Child's Slipper, of which the following is a specification, reference being had to the accompanying drawing, forming part thereof, wherein,

The characteristic feature of my design resides in the combination on the slipper disclosed of the high one piece seamless vamp specifically ornamented, as shown.

I claim:

The ornamental design for a child's slipper, substantially as shown and described.

MAX LINDER.
